AGRICULTURAL WINDROWING MACHINE

Constantine J. Kermes, Lancaster, Pa., assignor to Sperry
Rand Corporation, New Holland, Pa., a corporation of
Delaware

Filed Mar. 26, 1968, Ser. No. 11,149

Term of patent 14 years

(Cl. D40—1)

FIG. 1.

FIG. 2.

FIG. 3.

FIG. 1 is a perspective view of an agricultural windrowing machine looking at the machine from the left front, emphasizing in combination the header and front cab cowling features of my new design;

FIG. 2 is a side elevational view of the design of FIG. 1, as viewed from the side opposite that shown in FIG. 1; and

FIG. 3 is a top plan view of the design shown in FIGS. 1 and 2.

The back of the header is unornamented.

The dominant features of my design reside in the portions shown in full lines.

I claim:

The ornamental design for an agricultural windrowing machine, as shown and described.
